UNITED STATES PATENT OFFICE

96,188

DESIGN FOR A MOLDING FOR PIECES OF FURNITURE

Clarence G. Kimerly, Grand Rapids, Mich.

Application January 16, 1935, Serial No. 54,881

Term of patent 3½ years

To all whom it may concern:

Be it known that I, Clarence G. Kimerly, a citizen of the United States, residing at 2501 Leonard St., N. W., Grand Rapids, in the county of Kent and State of Michigan, have invented a new, original, and ornamental Design for a Molding for Pieces of Furniture, of which the following is a specification, reference being had to the accompanying drawing, forming a part thereof, in which:—

The figure is a perspective view of the molding, the distinguishing, essential and dominating feature or characteristic of the design being the

motif per se which is shown in full lines, the horizontal, vertical and lateral dimensions of the molding being shown in dotted lines and indicating non-essential features of the design since the molding may be used in the manufacture of numerous pieces of furniture, as for example with table tops, dresser rails, bed ends, mirror frames, chair backs and the like.

I claim:

The ornamental design for a molding for pieces of furniture as shown and described.

CLARENCE G. KIMERLY.
